United States Patent Office

Des. 207,982
Patented June 20, 1967

207,982

HAIR DRYER

Victor A. Petertil, Oak Park, and James Teague, Jr.,
Glenview, Ill., assignors to John Oster Manufacturing
Co., Milwaukee, Wis., a corporation of Wisconsin

Filed June 20, 1966, Ser. No. 2,738

Term of patent 14 years

(Cl. D86—10)

Fig. 1.

Fig. 2.

FIG. 1 is a perspective view of a hair dryer showing my new design with the hair drying hood of the hair dryer being in closed position;

FIG. 2 is a side elevation view of the hair dryer when viewed from the right hand side of FIG. 1;

FIG. 3 is a side elevation view similar to that of FIG. 2 but with the hood being in open position;

FIG. 4 is a sectional view taken along the section line 4-4 of FIG. 3;

FIG. 5 is a sectional view taken along the section line 5-5 of FIG. 4;

FIG. 6 is a top plan view when viewed from above FIG. 1; and

FIG. 7 is a side elevation view when viewed from the right hand side of FIG. 3.

We claim:

The ornamental design for a hair dryer, as shown.
